(57) **CLAIM**

The ornamental design for a multifunctional bottle with cap, as shown and described.

DESCRIPTION

FIG. 1 is a perspective view of the multifunctional bottle with cap showing the claimed design;

FIG. 2 is a top plan view thereof;

FIG. 3 is a rear elevational view thereof;

FIG. 4 is a left side elevational view thereof;

FIG. 5 is a front elevational view thereof;

FIG. 6 is a right side view thereof; and,

FIG. 7 is a bottom plan view thereof.

The broken lines shown illustrate portions of the multifunctional bottle with cap that form no part of the claimed design.
